UNITED STATES PATENT OFFICE

156,474

CABINET FOR A COMBINED RADIO, TELEVISION RECEIVER, AND PHONOGRAPH

Samuel E. Adler, Chicago, Ill.

Application July 29, 1948, Serial No. 147,837

Term of patent 14 years

(Cl. D56—4)

To all whom it may concern:

Be it known that I, Samuel E. Adler, a citizen of the United States, and resident of Chicago, in the county of Cook, State of Illinois, have invented a new, original, and ornamental Design for a Cabinet for a Combined Radio, Television Receiver and Phonograph, of which the following is a specification, reference being had to the accompanying drawings, forming a part thereof.

Fig. 1 is a front perspective view of a cabinet for a combined radio, television receiver and phonograph, showing my new design; and

Fig. 2 is also a perspective view of the cabinet but showing it in open condition.

I claim:

The ornamental design for a Cabinet for a combined radio, television receiver and phonograph, substantially as shown.

SAMUEL E. ADLER.
